Primary Examiner—Brian N. Vinson*Attorney, Agent, or Firm*—Richard C. Litman**[57]****CLAIM**

The ornamental design for a combination toiletry article holder and dispenser, as shown and described.

DESCRIPTION

FIG. 1 is a top, front, and right side perspective view of a combination toiletry article holder and dispenser showing my new design, the broken-line disclosure of toiletry articles being for illustrative purposes only and forming no part of the claimed design;
FIG. 2 is a front elevational view thereof;
FIG. 3 is a rear elevational view thereof;
FIG. 4 is a right side elevational view thereof, the left side being a mirror image of that shown;
FIG. 5 is a top plan view thereof; and,
FIG. 6 is a bottom plan view thereof.

FIG. 1

FIG. 2

FIG. 3

FIG. 4

FIG. 5

FIG. 6
